UNITED STATES PATENT OFFICE.

JOHN C. SCHEUFLER AND JOHN J. OSBURN, OF LOS ANGELES, CALIFORNIA.

FABRIC DISK WITH TOILET SOAP THEREON.

1,200,883.

Specification of Letters Patent. Patented Oct. 10, 1916.

Application filed January 17, 1916. Serial No. 72,634.

To all whom it may concern:

Be it known that we, JOHN C. SCHEUFLER and JOHN J. OSBURN, both citizens of the United States of America, both residing at 5 Los Angeles, county of Los Angeles, State of California, have invented a certain new and useful Fabric Disk with Toilet Soap Thereon; and we do hereby declare the following to be a full, clear, and exact description of the invention, such as will enable others skilled in the art to which it appertains to make and use the same.

This invention relates to fabric disks with toilet-soap thereon adapted for individual 15 use.

It is usual in hotels and other public places to provide a cake of toilet-soap which is used by many different individuals and which in consequence becomes unclean and 20 is often infected by germs or bacteria that spread disease.

The main object of this invention is the provision in a novel form of clean and sanitary toilet-soap adapted for individual use 25 by patrons of hotels and other public places.

Further objects of the invention are the provision of toilet-soap for individual use in a novel manner and form which makes it simple and inexpensive to manufacture, convenient and economical to use, highly satisfactory from the standpoint of cleanliness and hygiene, and practical and effective for accomplishing its purposes.

With the above objects in view the invention consists in producing a novel article of manufacture comprising a web, core, or disks, of inexpensive fabrics, such as paper, with toilet-soap thereon—the web being divisible into pieces having thereon sufficient 35 toilet soap to meet the requirements of individual use for one occasion.

The invention will be understood by those skilled in the art from a careful consideration of the following description taken in 45 connection with the accompanying drawings in which—

Figure 1 is a sectional view illustrating one form of apparatus for carrying out the process for producing the novel article of manufacture; Fig. 2 is a broken view of the web which carries the toilet-soap; and Fig. 50 3 shows views of one of the disks with layers of toilet-soap thereon.

The novel article of manufacture consists of a body or core 4 of suitable fabric—preferably waxed paper—having on one or

both sides thereof a layer of toilet-soap 5. The body or core 4 is preferably of such size and shape that it fits and may be rubbed between the hands of the user to remove 60 therefrom the toilet soap 5 which is substantially sufficient in quantity to meet the requirements of the user for one occasion. If more of the toilet-soap is required by the user, it can be had from another one of 65 the bodies or cores 4. The latter, as seen in Fig. 3, are preferably in the form of disks and are of substantially the size and shape of the palms of the hands. The fabric of the core or body 4 is preferably sufficiently pliable to make good suction contact with the 70 hands in use; so that it does not slip or shoot away from the hands but can easily be retained between the hands while the toilet soap is being rubbed off; also it is preferably sufficiently tough to prevent it from 75 rolling or breaking up while the toilet-soap is being rubbed off. When the user has rubbed off the toilet-soap 5 from the body or core 4 the latter being of cheap material is 80 thrown away. The article may be made in the form of a continuous strip or roll from which pieces may be torn off as required, or it may be made in the form of a chain of 85 easily separable disks—see Fig. 2, or it may be made in the form of separate pieces or disks of suitable size for single or individual use for one occasion.

In the practice of the invention on a large scale or for commercial purposes a web or strip 6 of fabric, preferably paper, is passed around the rollers 7, 8, 9, 10, 11, and 12, and it is wound on the roller 13. The rollers 8 and 10 are arranged in vats 14 and 15 which are placed in the heating tanks 16 and 17. 90 The latter may be heated by any suitable means such as by steam supplied through the piping 18 which is connected to the tanks 16 and 17. The upper interior portions of the tank 16 and 17 may be in communication through the pipe 19, and an exhaust pipe 20 may be in communication with the upper interior portion of the tank 17. In passing under the roller 8 the strip 6 when of paper passes through a bath 21 of heated paraffin wax in the vat 14 which 95 stiffens the paper and renders the paper tough and moisture proof. After leaving the vat 14 the strip 6 may be cooled to harden the wax by air blown through the 100 piping 22 or by other suitable means. In passing under the roller 10 the waxed strip 105

passes through a mass 23 of heated toilet-soap which adheres to the wax strip. After leaving the vat 15 the waxed strip with the toilet-soap thereon passes between the adjustable spaced blades 24 which scrape off the excess toilet-soap and insures even and uniform layers of the toilet-soap on the opposite sides of the waxed strip. To prevent any sticking together of the layers of toilet-soap when the strip is wound on the roller 13, powdered talc 25 or other suitable material is applied to the toilet-soap on one side of the strip by means of the mechanically operated sieve 26 or other suitable device.

We claim:

A new article of manufacture, consisting of a disk-form core of paper of substantially the size and shape of the palms of the hands

and coated with paraffin wax to stiffen and toughen it and render it waterproof, and then coated with toilet soap in sufficient quantity to meet the requirements of individual use for one occasion, the waxed core of paper being sufficiently tough and stiff to prevent it from breaking or rolling up in use, and it being sufficiently pliable to make good suction contact with the hands so that the toilet soap can be rubbed off of the waxed paper and the latter then thrown away, substantially as described.

In testimony whereof, we have signed our names to this specification at Los Angeles, county of Los Angeles, State of California, this 8th day of January, A. D. 1916.

JOHN C. SCHEUFLER.
JOHN J. OSBURN.
